United States Patent

Des. 237,749
Patented Nov. 18, 1975

237,749

TRAVEL CASE OR THE LIKE

Harriet P. McGrath, 1617 Alameda Ave.,
Alameda, Calif. 94501

Filed Oct. 12, 1972, Ser. No. 299,879

Term of patent 7 years

Int. Cl. D3—01

U.S. Cl. D87—5 G

FIG. 1 is a perspective view of a travel case or the like in open position showing my new design;

FIG. 2 is an elevational view;

FIG. 3 is a bottom plan view;

FIG. 4 is a top plan view;

FIG. 5 is a plan view of the interior;

FIG. 6 is a front elevational view; and

FIG. 7 is a rear elevational view thereof.

I claim:

The ornamental design for a travel case or the like, as shown.
